[57] ABSTRACT

A cosmetic organizer has a lower tray and an upper cover. The upper cover has an upper rim hinged to the lower tray. The upper rim has an erect annular wall. A relatively flexible upper shell overlays and is mounted flush on the erect annular wall. Thus, the shell has a soft feel but maintains an erect shape.

FIG. 3

FIG. 4

FIG. 5

FIG. 6

FIG. 7

FIG. 8

COSMETIC ORGANIZER

This is a continuation of application Ser. No. 07/913,803, filed Jul. 16, 1992, now U.S. Pat. No. 5,211,302.

BACKGROUND OF THE INVENTION

The present invention relates to cosmetic organizers and, in particular, to an organizer having a hinged cover.

A cosmetic organizer is helpful for keeping numerous small cosmetic items together and readily available. A complement of cosmetics can include numerous small items such as eyeliner pencils, lipsticks, compacts, various bottles, brushes, etc. Much time can be lost locating these various items when applying make-up.

It is desirable to keep such cosmetics in a closed case so they are not lost when transported or stored. It is also desirable to have a hinged cover and a catch to keep the cover closed. Preferably, the organizer is compartmentalized but not unnecessarily complex.

Furthermore the organizer should preferably be easily manufactured from simply molds. Known molds can make relatively complex shapes by using only two halves, or "plates." In some case a three part mold or a cam operated insert may be necessary if the shape is too complex for a two-plate mold. Still a shape such as a torus can be made with a "pass through," that is, an element that passes through the hole of the torus.

For aesthetic and practical reasons, a cosmetic case is preferably soft. A completely soft case, however, is disadvantageous because the case will collapse into a distorted shape making the case difficult to use.

Accordingly there is a need for an organizer that is compact, soft but not collapsible, which can be manufactured efficiently.

SUMMARY OF THE INVENTION

In accordance with the illustrative embodiments demonstrating features and advantages of the present invention, there is provided a cosmetic organizer having a lower tray and an upper cover. The upper cover has an upper rim hinged to the lower tray. The upper rim has an erect annular wall. A relatively flexible shell overlays and is mounted flush on the erect annular wall. Thus, the shell has a soft feel but maintains an erect shape.

By employing such a structure, a relatively attractive and efficiently manufactured organizer is achieved. In a preferred embodiment, the organizer has a pair of mating oval rims. Each of the rims has a curved and converging annular wall. These walls are relatively rigid, but have a relatively soft and flexible plastic shell glued to these walls. Thus the sides of the organizer can be relatively rigid, while the top is soft. This arrangement gives the general feel of softness without the problems associated with the collapsing.

In the preferred embodiment, the organizer has a partition mounted on the inside of the cover to form a pocket. The partition is a flexible net that is secured by its mounting holes to hooks mounted in the side wall of the rim.

The preferred organizer has a longitudinally ribbed top and bottom surface. The rims are also arranged to allow a sheet to be closed inside of the organizer, but still allowing a hang tab to emerge between the rims.

This feature enables the product to be hung from a display peg.

Other design features in the catch, the cover hinge and the hooks allow the organizer to be fabricated by a simple two plate mold using "pass throughs."

BRIEF DESCRIPTION OF THE DRAWINGS

The above brief description as well as other objects, features and advantages of the present invention will be more fully appreciated by reference to the following detailed description of presently preferred, but nonetheless illustrative embodiments, in accordance with the present invention, when taken in conjunction with the accompanying drawings, wherein:

FIG. 1 is a perspective view of a cosmetic organizer in accordance with the principles of the present invention;

FIG. 2 is a plan view of the bottom tray of the organizer of FIG. 1;

FIG. 3 is an inside view of the cover of the organizer of FIG. 1;

FIG. 4 is a cross sectional view taken along line 4—4 of FIG. 1;

FIG. 5 is a cross sectional view of a hook taken along line 5—5 of FIG. 3;

FIG. 6 is a detailed plan view of the hinge assembly of FIGS. 2 and 3 taken from the reverse side;

FIG. 7 is a detailed view of the catch of FIG. 3; and

FIG. 8 is a cross sectional view of the catch of FIG. 7 taken along line 8—8 of FIG. 7.

DETAILED DESCRIPTION OF THE PREFERRED EMBODIMENTS

Referring to FIG. 1, a cosmetic organizer is shown with an upper cover having a relatively flexible upper shell 10. Shell 10 is mounted in a upper rim 12. Upper rim 12 mates with lower rim 14 into which a relatively flexible lower shell 16 is mounted. Shell 16 and rim 14 together comprise a lower tray.

Cover 10 has a plurality of longitudinal stiffening ribs 18 for stiffening the shell. An embossment 20 is located in the middle of the ribs 18 for displaying a trademark, logo or other designation.

Rims 12 and 14 are held together by latch button 22, described in further detail hereinafter. Also, a shipping sheet, which may be made of a transparent acetate, is held inside the cosmetic organizer but has an apertured tab 24 shown emerging between rims 12 and 14.

In one embodiment the organizer was 7½ inches long, 5 inches wide, and 2 inches tall, although other sizes are contemplated, depending upon the desired capacity and the nature of the articles being held in the organizer.

Referring to FIGS. 2, 3, 4 and 5, rims 12 and 14 are shown as a channel having an erect annular wall 26 and a dependent annular wall 28, respectively. Walls 26 and 28 are curved and converging to provide a dome-like aspect to the organizer. Shell 10 and shell 16 each have annular flanges 11 and 17, respectively. Flanges 11 and 17 fit into the channels of rims 12 and 14, respectively.

Lower rim 14 has a guide wall 30 with a breach 32. Breach 32 is designed to allow the protrusion of the previously mentioned apertured tab (tab 24 of FIG. 1), which is part of sheet 25. Sheet 25 may be imprinted with various designs and can display the names or images of articles that can be stored inside the organizer.

Referring to FIGS. 3 and 5, nine hooks 42 are shown molded into annular wall 26. Hooks 42, when viewed in the plane of FIG. 3, are shown cantilevered over aper-

tures 44. Hooks 42 are not large enough to screen apertures 44. Thus hooks 42 can be molded with a two plate design using "pass throughs." Such a design avoids the need for additional mold elements or cam actions that would complicate the manufacturing process.

Hooks 42 are shown hooked into mounting holes in partition 46. Partition 46 has a grid of holes to form a net-like structure. Partition 46, as well as shells 10 and 16, are about $\frac{1}{8}$ inch thick and can be made of a soft PVC plastic (or another material such as rubber or thermoplastic rubber). The rims 12 and 14 can be made from a relatively rigid PVC plastic (or other materials such as ABS, polycarbonate, a high impact styrene or polypropylene). In other embodiments various different materials can be used including metals, ceramics, wood, leathers, etc.

Referring to FIGS. 2, 3 and 6, a hinge assembly is shown including four C-shaped sleeves 34. A pivoting structure 36 is shown with a plurality of spacers 38 and coaxial shafts 40. The three central spacers 38 interdigitate with the four C-shaped sleeves 34. The coaxial shafts 40 are sized to snap into the C-shaped sleeves 34. An advantage with the multiple spacers is the increased support provided along a relatively long shaft. While four sleeves are illustrated, in other embodiments a different number may be used.

Referring to FIGS. 7 and 8, previously illustrated latch button 22 is shown molded to span across a notch 48 in rim 12. Notch 48 allows the inward longitudinal ridge 50 on button 22 to be molded by a two plate process using "pass throughs." Ridge 50 is designed to snap around the underside of the opposing lower rim 14.

To facilitate an understanding associated with the principles of the foregoing invention, the use of the foregoing organizer will be briefly described. After molding, the flanges 11 and 17 of shells 10 and 16 can be placed the channels of rims 12 and 14. Preferably, the shells are glued in place, although other fastening techniques are possible such as solvent bonding or ultrasonic welding. Thereafter, the hinge may be snapped together by forcing shafts 40 into the C-shaped sleeves 34 (FIG. 6). Next, the partition 46 (FIG. 3) can be installed by pushing its mounting holes over hooks 42.

The user can now store various cosmetic items such as lipsticks, compacts, etc. Some of these items may be held in the pocket formed between partition 46 and shell 10. Once the articles are stored, the rims 12 and 14 can be closed and held together by latch 22.

Because shells 10 and 16 are relatively soft, the organizer has an aesthetically pleasing texture. However, the shells do not collapse because reinforcing walls 26 and 28 prevent the collapse or inversion of the soft shells.

It is to be appreciated that various modifications may be implemented with respect to the above described preferred embodiments. In some embodiments, the shape of the organizer can be more rectangular. Alternatively, the shape can be polygonal, spherical, or other desirable shapes. Also, the hinges can be of various types and in some cases a flexible band or joint will be formed between the rims. In addition, the latching can be performed by a swinging strap, a locking socket or other mechanisms. Furthermore, various materials can be used and in some cases metals, leathers, ceramics, and other materials may be substituted for those previously described.

Many modifications and variations of the present invention are possible in light of the above teachings. It

is therefore to be understood that within the scope of the appended claims, the invention may be practiced otherwise than as specifically described.

I claim:

- 5 1. A cosmetic organizer sized to store a plurality of cosmetics and having a thickness susceptible to grasping by hand, comprising:
a lower tray;
an upper cover attached to said lower tray and having an upper rim; and
a perforated partition having a top border, a bottom border and a pair of lateral borders and being mounted within said upper cover to form a pocket, said pocket being open at said top border and closed at said bottom border and said lateral borders, said partition being attached to said upper cover at said bottom border and said lateral borders, said partition being attached to said upper cover near said upper rim, said partition having a plurality of mounting holes, said upper cover having a circumferentially spaced plurality of attachment means for holding said partition by said mounting holes.
2. A cosmetic organizer according to claim 1 comprising a hinge connecting said upper cover and said lower tray, said upper rim being bisected by a longitudinal centerline, said partition occupying a region bordered by said hinge, said rim and said longitudinal centerline of said upper cover.
3. A cosmetic organizer according to claim 1 wherein said partition extends longitudinally and bifurcates the area encompassed by said upper rim.
4. A cosmetic organizer according to claim 1 wherein said partition occupies an area approximately half that encompassed by said upper rim.
5. A cosmetic organizer according to claim 1 wherein said partition is flexible.
6. A cosmetic organizer according to claim 1 wherein said upper cover and said lower tray comprise similar, complementary shells.
7. A cosmetic organizer according to claim 1 wherein said upper cover and said lower tray comprise similar, complementary shells, each having a pair of parallel side edges and a pair of semicircular end edges.
8. A cosmetic organizer according to claim 6 wherein at least one of said complementary shells has an outwardly extending rim.
9. A cosmetic organizer according to claim 6 wherein said complementary shells each has an outwardly extending rim.
10. A cosmetic organizer according to claim 6 wherein said complementary shells are each encompassed by a curved and converging side wall.
11. A cosmetic organizer according to claim 7 wherein said complementary shells are each encompassed by a curved and converging side wall.
12. A cosmetic organizer according to claim 11 wherein the thickness of said organizer is less than half the width of said organizer.
13. A cosmetic organizer according to claim 12 wherein each of said shells has a length to width ratio of approximately 1.5.
14. A cosmetic organizer according to claim 1 wherein said upper cover comprises:
a latch for extending to said lower tray and holding closed said lower tray and upper cover.
15. A cosmetic organizer according to claim 6 comprising:

a guide wall mounted on either one of said shells and sized to fit inside the other one of said shells.

16. A cosmetic organizer sized to store a plurality of cosmetics and having a thickness to width ratio smaller than one and being susceptible to grasping by hand, comprising:

a lower shell;

an upper shell having an upper rim that extends outwardly and a latch for extending to said lower shell and holding closed said lower and said upper shells; and

a perforated partition mounted within said upper shell near said upper rim to form a pocket, said partition occupying an area approximately half that encompassed by said upper rim, said upper shell having a circumferentially spaced plurality of attachment means for holding said partition, said upper and said lower shells being similar and complementary, and each having:

(a) a pair of parallel side edges and a pair of semicircular end edges,

(b) a perimeter with a curved and converging side wall, and

(c) a length to width ratio exceeding one.

17. A cosmetic organizer according to claim 1 wherein said upper cover is encompassed by a curved and converging side wall, a portion of said side wall being canopied over the top border of said partition.

18. A cosmetic organizer sized to store a plurality of cosmetics and having a thickness susceptible to grasping by hand, comprising:

a lower tray;

an upper cover having an upper rim and being attached to said lower tray; and

a perforated partition mounted within said upper cover to forth a pocket, said partition being attached to said upper cover near said upper rim, said partition having a plurality of mounting holes, said upper cover having a circumferentially spaced plurality of attachment means for holding said partition by said mounting holes.

19. A cosmetic organizer according to claim 18 comprising a hinge connecting said upper cover and said

lower tray, said upper rim being bisected by a longitudinal centerline, said partition occupying a region bordered by said hinge, said rim and said longitudinal centerline of said upper cover.

20. A cosmetic organizer according to claim 18 wherein said partition extends longitudinally and bifurcates the area encompassed by said upper rim.

21. A cosmetic organizer according to claim 18 wherein said partition occupies an area approximately half that encompassed by said upper rim.

22. A cosmetic organizer according to claim 18 wherein said partition is flexible.

23. A cosmetic organizer according to claim 18 wherein said upper cover and said lower tray comprise similar, complementary shells.

24. A cosmetic organizer according to claim 18 wherein said upper cover and said lower tray comprise similar, complementary shells, each having a pair of parallel side edges and a pair of semicircular end edges.

25. A cosmetic organizer according to claim 18 wherein at least one of said complimentary shells has an outwardly extending rim.

26. A cosmetic organizer according to claim 18 wherein said complimentary shells each has an outwardly extending rim.

27. A cosmetic organizer according to claim 18 wherein said complimentary shells are each encompassed by a curved and converging side wall.

28. A cosmetic organizer according to claim 18 wherein the thickness of said organizer is less than half the width of said organizer.

29. A cosmetic organizer according to claim 18 wherein each of said shells has a length to width ratio of approximately 1.5.

30. A cosmetic organizer according to claim 18 wherein said upper cover comprises:

a latch for extending to said lower tray and holding closed said lower tray and upper cover.

31. A cosmetic organizer according to claim 18 comprising:

a guide wall mounted on either one of said shells and sized to fit inside the other one of said shells.
